ATTORNEY:-

UNITED STATES PATENT OFFICE.

LESLIE WASHBURNE TAYLOR, OF BOURNEMOUTH, ENGLAND.

TOBACCO PIPE.

Application filed September 25, 1926, Serial No. 137,735, and in Great Britain October 6, 1925.

This invention relates to tobacco pipes and has for its chief object to provide movable means for dividing the bowl of the pipe into an upper or main tobacco receiving portion 5 and a lower chamber for containing absorbent material. The device for thus dividing the bowl of the pipe comprises a movable perforated diaphragm or disc which can be turned or moved easily into and out of position to allow for the insertion and extraction of the absorbent substance when desired.

Referring to the accompanying drawings:—

Fig. 1 is a side elevation of a pipe constructed in accordance with or embodying the present invention.

Fig. 2 is a sectional elevation of the pipe shown in Fig. 1.

Fig. 3 is a sectional plan on the line 3—3 of Fig. 1, showing the movable diaphragm in normal position, and Fig. 4 is a similar view showing the diaphragm in the withdrawn position.

The bowl and stem of the pipe are in accordance with the usual form or design and the present invention may be applied to pipes of known construction.

In accordance with the present invention, a horizontal saw cut or slot *a* is shown formed in the bowl *b* of the pipe a short distance above the lower end thereof, and may extend about half way across the bowl.

In the example illustrated a disc or diaphragm *c* is mounted by one corner on a pivot or pin *d* driven upwards into the edge of the bowl *b* (see Fig. 1). This disc has a central solid portion in which is a central hole or opening *e*, and in the normal position the diaphragm *c* lies or is flush with the outer walls of the pipe bowl, and divides the interior of said bowl into an upper or tobacco-containing chamber *h* and a lower or absorbent-containing chamber *k*.

In order to minimize or eliminate any tendency of the disc to stick or difficulty in moving it, the portion of the disc which lies within the slot *a* is cut way at *m*.

The disc or diaphragm *c* is cut or made to conform to the extent of the slot *a* so as to fit closely therein and prevent the ingress of 50 air, and also so that one end wall of the slot acts as a stop for the disc.

The disc is also shown furnished with a handle, finger-grip or the like *n* to facilitate the opening and closing movement of 55 said disc, and as this handle projects outside the bowl, it radiates or dissipates heat conducted from the part of the disc within the bowl.

The disc or diaphragm *c* is a comparatively tight fit or sliding fit in the slot *a*, and although in the present example it is of uniform thickness throughout, this is not essential, and a disc made of reduced thickness within the bowl for facilitating the removal of deposit thereon would not affect the invention herein described. The form of the finger-piece *n* is obviously a matter of preferred design.

By moving the disc *c* the central opening *e* 70 can be readily cleaned, without removal of the contents of the pipe, and the disc in the closed position enables the contents of the upper chamber *h* to be pressed down without danger of choking or clogging the bore *o* 75 of the pipe stem.

Appropriate material of an absorbent nature may be placed in the chamber *k*, and removed when desired after the disc *c* has been withdrawn.

I claim:—

In a tobacco pipe, a movable and perforated disc normally dividing the interior of the bowl longitudinally into an upper and a lower chamber, said disc pivoted on the bowl 85 for removal from the interior of the latter, a slot in the bowl for receiving said disc, a finger device in connection with said disc for effecting the movement of the latter in and out of the bowl interior, substantially as 90 herein set forth.

In testimony whereof he hath affixed his signature.

LESLIE WASHBURNE TAYLOR.
